CLAIM

The ornamental design for a multifunctional lamp, as shown and described.

DESCRIPTION

FIG. 1 is a perspective view of the multifunctional lamp showing my new design;

FIG. 2 is a bottom plan view thereof;

FIG. 3 is a left elevation view thereof;

FIG. 4 is a right elevation view thereof;

FIG. 5 is a front elevational view thereof;

FIG. 6 is a rear elevational view thereof; and,

FIG. 7 is a top plan view thereof.

The portions of the disclosure shown in broken lines form no part of the claimed design.
